Primary Examiner — Derrick E Holland(74) *Attorney, Agent, or Firm* — Thomas C. Feix**CLAIM**

The ornamental design for a combustible briquet, as shown and described.

DESCRIPTION

FIG. 1 is a front perspective view of a combustible briquet showing our new design (front and rear perspective views are identical);

FIG. 2 is a top view of the design of FIG. 1 (top and bottom views are identical);

FIG. 3 is a front elevational view of the design of FIG. 1 (front, right, left side and right side views are identical);
FIG. 4 is a cross-sectional view of FIG. 2 along axis 9-9; and,

FIG. 5 is a cross-sectional view of FIG. 2 along axis 10-10. The broken lines in FIG. 2 represent the cross-sectional designations and form no part of the claimed design.
